(57) **CLAIM**

The ornamental design for a religious display sign, as shown and described.

DESCRIPTION

FIG. 1 is a front elevational view of a religious display sign showing my new design;

FIG. 2 is a rear elevational plan view thereof;

FIG. 3 is a right side elevational view thereof;

FIG. 4 is a left side elevational view thereof;

FIG. 5 is a top plan view thereof; and,

FIG. 6 is a bottom plan view thereof.

The broken lines shown on FIGS. 1 and 2 are for illustrative purposes only and are hereby disclaimed as forming no part of Applicant's claimed invention.
